CAR AND ELECTRIC COUPLING.

1,290,117.

Specification of Letters Patent.

Patented Jan. 7, 1919.

Original application filed January 3, 1914, Serial No. 810,112. Divided and this application filed March 8, 1917. Serial No. 153,436.

To all whom it may concern:

Be it known that we, EDWARD H. DEWSON, of the borough of Manhattan, in the city, county, and State of New York, and THOMAS R. BROWN, of Sparkill, in the county of Rockland and State of New York, have invented a certain new and useful Improvement in Car and Electric Couplings, of which improvement the following is a

10 specification.

This invention relates to car coupling devices and mechanism for coupling electric train line circuits, between the cars or other vehicles of the train, and more particularly 15 to that type of car and electric coupler in which each counterpart coupling head has a plurality of contacts connected to the respective train line circuits, and a movable contact carrier, one of said carriers being 20 adapted to be projected to bridge over the space and establish electrical connection between the corresponding contacts of the two couplers when the same are coupled together. With this type of coupler, particu- 25 larly where there is a relative lateral movement between the coupler heads in uncoupling, it is important that the movable contact carrier be withdrawn from its projected position before the couplers are released 30 and pulled apart, in order to avoid liability of breakage and damage to the same, and the object of our present invention is to provide improved means whereby said contact carrier shall be withdrawn before the 35 couplers are released.

This application is a division of our original application Serial No. 810,112, filed January 3, 1914, in which different modifications are shown for controlling the movement 40 of the contact carrier and the release of the coupler lock, and our present improvement comprises means governed by the movement of the contact carrier for controlling the release of the coupler.

45 In the accompanying drawings: the figure is a diagram, partly in plan and partly in section, showing a pair of couplers locked together and embodying one form of our improvement.

50 According to the construction shown in the drawing, the coupler comprises a main casting or coupler head, 12, adapted to be secured by a pivotal connection, 13, to a draw bar, and having a hook shaped projection, 14, provided with a vertical plane

surface inclined at an angle to the line of draft and adapted to engage and interlock with a corresponding surface on the projection of a counterpart coupler by a relative lateral movement when said couplers 60 come together in the act of coupling. Each coupler head is also provided with a pivoted lock, 16, adapted to bear against a locking surface, 17, on the outer side of the projection, 14, of the counterpart coupler, and hold the couplers securely clamped together when in coupled position.

For the purpose of releasing the lock of the coupler, fluid pressure means are provided, comprising a cylindrical chamber formed in the coupler head and containing a piston, 18, which is connected by a rod, 19, with an arm of the pivoted lock, 16, a spring, 20, acting on the back of the piston to normally hold the lock in its locking position. Fluid under pressure, such as compressed air, may be admitted through passage, 22, and port, 23^a, to the cylinder for actuating the piston, 18, to compress the spring and turn the pivoted lock, 16, to its 80 releasing position when it is desired to uncouple and separate the couplers.

The casing, 41, for containing the electric contact device is supported beneath the under side of the coupler head in such position that the adjacent ends of the two casings of the counterpart couplers meet together when coupled. In the casing, 41, are mounted a plurality of contact fingers, 43, preferably in a horizontal row, near the 90 outer end of the casing, and each connected with a corresponding wire of the train line circuits. Other sets of contact fingers, 45, may be employed for closing certain local circuits upon each car.

In order to establish electrical connection between the respective contact fingers of the counterpart couplers, there is a sliding contact carrier, 46, mounted in the casing and having a plurality of sets of contact bars, 47 and 48, 100 properly connected and adapted to engage the sets of contact fingers, 43, of the adjacent counterpart couplers when coupled together with one of the slides extended into the casing of the other coupler, whereby the 105 contacts of the movable carrier bridge over the space between the said sets of contact fingers, and establish the desired electrical connection. The contact bars, 47 and 48, are preferably cross connected on opposite 110

sides of the center line. Other contact bars, 49, may also be carried by the slide for establishing certain connections between the contact fingers, 45.

5 The contact carrier may be operated by any suitable means, but as herein shown, there is provided a cylinder, 77, containing a piston, 78, connected to an arm, 79, for actuating the slide, 46, the supply of fluid 10 to the cylinder being controlled by any suitable valve means, such as puppet valve, 80, governing the admission of fluid from passage, 81, to the port, 82, leading into the cylinder, 77, and the exhaust valve, 83, controlling the release from the cylinder to the atmosphere.

In order that the valve mechanism may be operated automatically by the coming together of the counterpart couplers, the valve, 20 80, is normally seated by a spring, 84, and abuts against the stem of the exhaust valve, 83, which is mounted on the stem or rod, 38, which extends longitudinally through the casing, preferably on the center line, and 25 projects a short distance beyond the end of the casing in a position to abut against the end of the corresponding rod of the counterpart coupler when the same are brought together in the act of coupling. The exhaust 30 valve, 83, may be slidably mounted on the rod, 38, with a yielding spring, 85, located between the same. As the two couplers come together, the rod, 38, is forced inward to open the valve, 80, and close the valve, 83, 35 thereby admitting fluid to the piston, 78, to actuate the movable contact carrier to its outer position in which the train line circuits of the adjacent cars are coupled together. The device is designed so that one of the 40 projecting rods shall yield and be forced inward before the other when the couplers come together, and with this arrangement, the slide, 46, is adapted to occupy a normal intermediate position with its end close to 45 the opening in the casing when the couplers are separated. The force which opposes the yielding inward movement of the rod, 38, is due to the pressure of the spring, 84, and the fluid pressure acting on the back of the valve, 50 80, which is of a comparatively large area, and since these conditions are never precisely alike and exactly equal in all respects in any two counterpart couplers, it is evident that one of the valves of said couplers 55 will start to yield before the other thereby cracking the joint of the valve upon its seat, and admitting pressure beneath the same which instantly balances the valve as to fluid pressure and thereby eliminates most of the 60 opposing force. The corresponding rod then readily yields, being forced inward by the projecting rod of the counterpart coupling, and the piston, 78, moves the slide, 46, outward through the narrow opening and into 65 the casing of the other coupler, where it en-

gages the corresponding slide and forces the same back to its extreme inner position, as shown in the drawing. In this position, the respective sets of contact fingers, 43, of the train line circuits are connected while the 70 local circuits, which are closed by contacts, 45 and 49, in the intermediate position of the slide, are open.

Each sliding contact carrier is provided with a projection, 90, extending between the 75 springs, 86 and 86^a, which, in the normal release position, rest against the abutment, 91, one spring opposing the movement of the slide in one direction from its normal intermediate position, and the other spring opposing the movement of the slide in the opposite direction from said position.

In releasing the coupler, it is desirable that the sliding contact carrier should be withdrawn before the coupler locks are released and before the coupler heads begin to separate, and particularly so where the initial movement of the coupler heads relative to each other is, in a laterally inclined direction, as in the present case, and it is also desirable that the operator should be able to withdraw the slide during the time that the coupler heads are locked together and without uncoupling the same. According to this feature of our improvement, a valve device 90 is provided for controlling the release of air from the actuating cylinder, 77, when the exhaust valve, 83, is closed. As shown in the drawing, this valve device for controlling the release of the slides is located between the tappet valve, 80, and the slide actuating cylinder, 77, and comprises a piston, 24^a, having a stem for actuating the valve, 26^a, which controls the passage, 82, normally permitting free communication from the supply passage, 37, and valve, 80, through said passage, 82, to the cylinder, 77, but adapted to close said communication and vent air from the cylinder through exhaust port, 29^a, to the atmosphere when fluid pressure is admitted, by cock, 21^a, through connection, 21, to the piston, 24^a.

In order to prevent the release of the coupler locks before the return of the slides to normal position, we have shown a valve governed by the movement of the slides for controlling the passage leading to the unlocking cylinders. This valve, 95, is in the form of a round headed plunger resting on the slide, 46, and having a spring, 96, pressing the valve against the slide. When the slides occupy the coupled position, the valves, 95, are held up in such position as to close communication from the passage, 22, to the port, 23^a, and the unlocking cylinders, and to open the exhaust port, 98. When, however, the slides are returned to their normal positions, the recess, 97, is brought in line with the valve, and the spring forces the same down thereby closing the exhaust port and open- 130

ing free communication from passage, 22, to the port, 23^a, and the unlocking cylinder. By means of this interlocking feature, it is impossible for the fluid pressure to reach the 5 unlocking pistons, 18, until the slides have returned to normal position.

In the coupling up operation the action is substantially the same as before described, one of the tappet valves opens to 10 admit pressure from the supply passage, 37, through passage, 82, to the slide projecting cylinder, 77, of one of the couplers, thus actuating the slides, 46, to make the electric train line connections. When it is desired 15 to release the couplers, fluid pressure is admitted by a suitable cock 21^a, on either vehicle to the pipe connection, 21, and thence flows by passage, 22, and the bore, 39, of tappet, 38, to the corresponding passages 20 of the counterpart coupler, moves the corresponding valve, 26^a, against its spring, and thereby releases the pressure from the cylinder, 77, which allows the slides to return, by means of their springs, to normal position. The valves, 95, then move to open position, and supply fluid to the unlocking cylinders of both couplers, and the same may then be pulled apart, after which the 25 pressure escapes from passages, 39 and 22, and the pistons, 24^a, and valves, 26^a, return to normal position.

While we have shown one form of interlocking means governed by the movement of contact carrier or slide for controlling the 30 release of the coupler lock, it will be evident that our improvement is not limited to this particular construction, but extends to various forms of mechanism which may readily be designed for this purpose.

Having now described our invention, what we claim as new and desire to secure 35 by Letters Patent is:

1. In a car coupling, the combination of a coupler head having a movable lock, a device 40 for releasing said lock, electrical contacts connected to the respective train line circuits, a movable carrier having corresponding contacts, means for projecting and withdrawing said carrier, and means governed by the movement of said carrier for controlling the release of the coupler lock.

2. In a car coupling, the combination of a coupler head having a movable lock, a device 45 for releasing said lock, electrical contacts connected to the respective train line circuits, a movable contact carrier, a fluid pressure operated device for projecting said

carrier to electrically connect corresponding contacts of counterpart couplers, means for effecting a return movement of said carrier, 60 and means governed by the movement of said carrier for controlling the release of the coupler lock.

3. In a car coupling, the combination of a coupler head having a movable lock, a fluid 65 pressure device for releasing said lock, electrical contacts connected to the respective train line circuits, a movable carrier having corresponding contacts, means for projecting and withdrawing said carrier, and 70 means governed by the movement of said carrier for controlling the supply of fluid to the device for releasing the coupler lock.

4. In a car coupling, the combination of a coupler head having a movable lock, a piston 75 for releasing said lock, electrical contacts connected to the respective train line circuits, a movable carrier having corresponding contacts, means for projecting and withdrawing said carrier, and a valve governed by the movement of said carrier for 80 controlling the supply of fluid to the unlocking piston of the coupler lock.

5. In a car coupling, the combination of a coupler head having a movable lock, a fluid 85 pressure device for projecting said carrier to electrically connect corresponding contacts of counterpart couplers, means for effecting a return movement of said carrier, and means governed by the movement of said carrier for controlling the supply of fluid to 90 release the coupler lock.

6. In a car coupling, the combination of a coupler head having a movable lock, a device for releasing said lock, electrical contacts connected to the respective train line 100 circuits, a movable contact carrier, a fluid pressure operated device for projecting said carrier to electrically connect corresponding contacts of counterpart couplers, a fluid pressure operated valve device controlling 105 the release of fluid to effect a return movement of the carrier, and means governed by the movement of said carrier for controlling the release of the coupler lock.

In testimony whereof we have hereunto set 110 our hands.

EDWARD H. DEWSON.
THOMAS R. BROWN.

It is hereby certified that Letters Patent No. 1,290,117, granted January 7, 1919, upon the application of Edward H. Dewson, of New York, and Thomas R. Brown, of Sparkill, New York, for an improvement in "Car and Electric Couplings," were erroneously issued to the inventors, said Dewson and Brown, whereas said Letters Patent should have been issued to *The Westinghouse Air Brake Company, of Pittsburgh, Pennsylvania, a corporation of Pennsylvania*, as shown by the records of assignments in this office; and that the said Letters Patent should be read with this correction therein that the same may conform to the record of the case in the Patent Office.

Signed and sealed this 25th day of February, A. D., 1919.

[SEAL.]

F. W. H. CLAY,

Acting Commissioner of Patents.

Cl. 213—40.
